US0D1015659S

(12) **United States Design Patent** (10) **Patent No.:** **US D1,015,659 S**
(45) **Date of Patent:** **** Feb. 20, 2024**

(54) **BLOWER**

(71) Applicant: **Zhejiang Prulde Electric Appliance Co., Ltd., Zhejiang (CN)**

(72) Inventors: **Weiming Yang, Zhejiang (CN); Ting Han, Zhejiang (CN)**

(73) Assignee: **Zhejiang Prulde Electric Appliance Co., Ltd., Zhejiang (CN)**

(**) Term: **15 Years**

(21) Appl. No.: **29/755,158**

(22) Filed: **Oct. 19, 2020**

(30) **Foreign Application Priority Data**

Apr. 17, 2020 (CN) 202030156440.2

(57) **CLAIM**

The ornamental design for a blower, as shown and described.

DESCRIPTION

FIG. 1 is a perspective view of a blower showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, wherein a battery is assembled to the blower.

The broken lines shown in the figures and the lower opacity areas within the broken lines, is for the purpose of illustrating portions of the blower that form no part of the claimed design. The battery shown in the FIG. 8 drawing view in the broken lines and the lower opacity areas within the broken lines is for environmental and illustrative purposes only and form no part of the claimed design.

1 Claim, 8 Drawing Sheets
